UNITED STATES PATENT OFFICE

WESLEY P. SHOMAKER, OF RICHMOND, VIRGINIA

PERFORATOR

Application filed August 26, 1931. Serial No. 559,582.

The present invention relates to perforators, and more particularly to a perforator for use in connection with envelopes, sheets and other like articles across which it is desired to form a line of perforations.

An object of the present invention is to provide a perforator with improved means for temporarily rendering the same inoperative in connection with certain envelopes or sheets which pass through the mechanism and which may be operated by striker fingers or other trip means, such as disclosed in connection with co-pending application Serial No. 557,165, filed August 14, 1931.

Another object of the present invention is to provide a support for a perforating disc, which normally holds the disc in position for operation upon the envelope, but which when tripped will automatically raise the perforating disc out of the line of contact with the envelope, so that the disc may be maintained at a constant predetermined speed of rotation to prevent injury to the disc and envelope when the disc is again released and moved into operating position.

It is a further object of the invention to provide a construction of this character wherein there is a minimum amount of strain on the operating mechanism when in operation and also when tripped.

The invention also aims to provide a mechanism wherein the edge of the envelope is not upset as it is brought into contact with the perforator, the object being carried out by the continuous and uninterrupted rotation or driving of the perforating disc.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a side elevation of a perforator constructed according to the present invention, the trip mechanism being shown in dotted lines, and

Figure 2 is an end view whereof with the perforating disc in operative position in full

lines and in retracted position in dotted lines.

Referring to the drawing 10 designates a cylinder over which envelopes 11, sheets or other articles to be perforated are passed, the same being moved between the cylinder 10 and a perforating disc 12. The disc 12 is provided with pointed teeth, or given any other suitable construction to form the perforations in the envelope 11, and the disc 12 is mounted upon a shaft 13 which carries clamping discs 14 secured to the shaft at opposite sides of the perforating disc 12 to secure the latter firmly to the shaft.

The shaft 13 is provided on one end with a removable washer 15 which is secured to the shaft by a screw 16 or the like while the opposite end of the shaft 13 carries a pulley 17 by means of which the shaft is continuously rotated. The opposite ends of the shaft 15 are mounted in bearing arms 18 and the washer 15 is adapted to engage against the outer face of one of the arms 18, so as to hold the shaft 13 from longitudinal displacement from the arms. The arms 18 are provided at one edge, and intermediate their ends, with shoulders 19 and the upper ends of the arms 18 are connected to springs 20 which extend upwardly from the arms and rearwardly at opposite sides of the bracket head 21 for normally urging the arms 18 in an upward direction and also to swing rearwardly against the opposite sides of the head 21. The head 21 is provided at its lower end with spaced depending fork arms 22 which are disposed at opposite sides of the discs 12 and 14 and which are provided with longitudinal slots 23 in which is freely slid able the opposite end portions of the shaft 13, so that the shaft with the perforating disc 12 may move lengthwise within the fork arms 22 toward and from the cylinder 10.

The head 21 is provided at opposite sides with downwardly facing shoulders 24 adapted to receive thereagainst the shoulders 19 of the bearing arms 18 when the latter are swung forwardly against the tension of the springs 20 for holding the perforating disc 12 against the cylinder 10. The bracket head 21 is provided with inclined or cam faces 25 at the rear ends of the shoulders 24 and over

which the shoulders 19 of the arms are adapted to engage to force the arms 18 downwardly or lengthwise of the fork 22 as the arms 18 are swung forwardly.

5 The bracket head 21 is provided in its upper end with a socket 26 and in one side with a set screw 27 adapted to enter the socket and engage against the side of a bracket arm 28 for adjustably holding the bracket head on the arm, and the arm is provided with a clamp 29 adapted to engage a supporting frame rod 30 for rigidly holding the arm in adjusted position thereon.

10 Spaced lengthwise of the supporting frame rod 30 is a socket clamp 31 carrying a set screw 32 adapted to engage against a bearing arm 33, which is seated in the socket of the clamp 31 and which is provided at its outer end with a bearing 34 adapted to retain there-in a rock shaft 35, which is disposed substantially in parallel relation with the frame rod 30. The shaft 35 carries at one side thereof a sleeve 36 engaging against one side of the bearing 34 and which is fixed in desired angular relation upon the shaft 35 by a set screw 37.

15 The sleeve 36 is provided at one side with a radially disposed post or stud 38 to which one end of a spring 39 is secured, the other end of the spring being looped or otherwise secured upon the frame rod 30, so as to exert tension upon the sleeve 36 and the shaft 35 to turn in one direction.

20 The rock shaft 35 is provided upon its end and at the opposite side of the bearing 34 with a crank arm 40 to which is pivoted a trip rod 41 which extends to a suitable point of the envelope handling mechanism and which, as shown in dotted lines in Figure 1, 25 may be connected to a spring pressed lever 42 lying in the path of a striker finger 43 for swinging the lever 42 and moving the rod 41 at times.

25 The rock shaft 35 is provided upon its opposite end with an end socket 44 adapted to interfit with the non-circular end of a cam shaft 45, which is journaled through the rear end portion of the bracket head 21, and which practically constitutes the rear edges of the fork arms 22. The cam shaft 45 carries a 30 pair of cams 46 which are disposed against the opposite outer faces of the fork arms 22 in line with the bearing arms 18, and are adapted, as shown in Figure 2, to engage 35 against the rear edges of the arms 18 and swing the latter forwardly against the tension of the springs 20 when the rock shaft 35 and the cam shaft 45 are turned.

40 In use, the clamps 29 and 31 may be adjusted lengthwise of the supporting frame rod 30 to dispose the perforating disc 12 in line with the portions of the envelopes or sheets 11 which are to be perforated as they move over the cylinder 10. The correct adjustment 45 of the disc 12 with respect to the cylinder

10 may be obtained by moving the bracket head 21 on the bracket arm 28 and securing the parts in adjusted position by the set screw 27. The corresponding adjustment is also made between the clamp 31 and the bearing arm 33, the latter being moved in the socket of the clamp 31 and fixed in adjusted position by the set screw 32.

15 The disc 12, through the pulley 17 is continuously rotated at a predetermined speed 75 with respect to the rotation of the cylinder 10 and the feeding of the envelopes 11, so that the disc 12 is maintained at a constant speed of rotation at all times.

20 Normally, the spring 39 holds the rock shaft 35 and the cam shaft 45 in such position as to maintain the cams 46 against the bearing arms 18 and hold the shoulders 19 thereof beneath the shoulders 24 of the bracket head 21. This maintains the bearing arms 25 19 in an outwardly shifted position, so as to hold the perforating disc 12 in position to engage the envelopes 11 as the latter are fed over the cylinder 10.

25 At certain times it may be desired to prevent the perforating of desired envelopes or sheets 11, and for this purpose, the mechanism is provided with one or more striker fingers 43 adapted to engage the lever 42 of the machine and thus move the rod 41 of the perforator. The rod 41 swings the arm 40 in a direction to turn the rock shaft 35 against the tension of the spring 39. The rock shaft 35 turns the cam shaft 45 and swings the cams 46 backwardly away from the bearing arms 18. The springs 20 now draw the bearing arms 18 backwardly from beneath the shoulders 24 of the bracket head 21 and at the same time drawing the arms 18 upwardly to an extent sufficient to raise the perforating disc 12 out of the line of contact with the envelopes or sheets 11. This action is permitted as the cam or inclined faces 25 at the rear ends of the shoulders 24 extend upwardly and rearwardly, so that the shoulders 19 of the bearing arms may ride upwardly over the faces 25 and thus admit of the upward sliding movement of the shaft 13 in the slots 23 of the fork 22. When the disc 12 is thus retracted, it is still maintained in a state of rotation with the speed unchanged.

30 Thus when the rod 41 is released, the spring 39 returns the parts to normal position and the cams 46 force the bearing arms 18 forwardly and downwardly to interlock the shoulders and move the perforating disc 12 back into the line of operation. There will be no slipping, jarring or upsetting of the teeth with respect to the perforating disc 12, and there will thus be no mutilation of the envelopes 11 during this return movement of the perforating disc. The operation is automatic and smooth without jar or sudden take-up of any of the parts which are adapted

to rotate when operating. It is also seen that the adjustment may be quickly and easily effected as the rock shaft 35 is detachably engaged with the cam shaft 45 by means of the end socket 44 of the rock shaft. The bracket head 21 may thus be first adjusted into the proper line of feed with respect to the envelopes 11, and after this adjustment is obtained the rock shaft 35 with its connected and supporting parts may then be adjusted to accommodate the adjustment of the perforating disc 12.

It is obvious that various changes and modifications may be made in the details of construction and design of the above specifically described embodiment of this invention without departing from the spirit thereof, such changes and modifications being restricted only by the scope of the following claims:

What is claimed is:—

1. In a perforator for envelopes and the like passing over a cylinder, a bracket head, a shaft mounted in the outer end of the head and adapted for bodily movement therein toward and from the cylinder, means for continuously turning the shaft, a perforating disc mounted on the shaft, means for maintaining the perforating disc normally in the line of feed of the envelopes, and automatic trip actuated means operable on the shaft for shifting the same in the bracket head to at times retract the perforating disc from the cylinder.

2. In a perforator for envelopes passing over a cylinder, a perforating disc, shiftable supporting means for the disc, means for continuously turning the disc, yieldable means normally urging the disc from the cylinder out of the line of operation on the envelopes, spring means operable on said first means for normally maintaining the latter in position to project the perforating disc into the line of feed for operation on the envelopes, and trip means operable on said last named means for rendering the same inoperative to admit operation of the first means and the retraction of the perforating disc.

3. In a perforator, a perforating disc, means for continuously rotating the disc, means for retracting the disc out of operative position, releasable means normally acting on said retracting means to maintain the disc in projected position for operation, and trip means operable upon said releasable means for actuating the latter to release the retracting means; whereby said disc may be retracted.

4. In a perforator, a bracket, means for supporting the bracket, a shaft movably mounted in the bracket into projected and retracted positions, a perforating disc mounted on the shaft, bearing members for said shaft, said bearing members and said bracket having interlocking shoulders for maintaining

the bearing members and the shaft in projected position, springs between the bearing members and the bracket for normally moving the bearing members to disengage the shoulders and retract the bearing members and the shaft, a cam shaft mounted on the bracket, cams on the cam shaft for engaging the bearing members to move the same into projected position and interlock the shoulders, a rock shaft connected to the cam shaft, spring means engaging the rock shaft to urge the same to turn in a direction to hold the cams against said bearing members and maintain the latter in projected position, and trip means connected to the rock shaft for at times to turn the latter against the spring and relieve said cams from pressure against the bearing members, whereby the springs of the bearing members may retract the latter.

5. An envelope perforator comprising a bracket head, means for adjustably supporting the bracket head, said bracket head having a slotted fork at its outer end and outwardly facing shoulders with backwardly and inwardly inclined cam faces leading from the shoulders at opposite sides of the fork, a pair of bearing arms disposed at opposite sides of the fork, a shaft mounted in said bearing arms, a disc mounted on the shaft in the fork, means for continuously turning the disc, cam means mounted on the bracket head for moving said bearing arms against said cam faces and beneath the shoulders of the bracket head to maintain the shaft and disc in projected position, spring means connected between the bearing arms and the bracket head for urging the spring arms inwardly and rearwardly of the head for retracting the shaft and the perforating disc, a spring operated rock shaft connected to the cam means for normally urging the cam means against said bearing arms, and trip operated means connected to the rock shaft for moving the same in a direction to relieve the cam means from the bearing arms.

6. In a perforator adapted to perforate envelopes or the like passing over a cylinder, a perforating disc, supporting means for the disc, means for rotating the disc, locking means biased to a released position for holding the disc in the line of feed of the envelopes, and trip releasable means normally operable on the locking means for holding the disc toward the cylinder in said line of feed.

7. A perforator comprising a clamp adapted for attachment to a machine frame, a bracket arm on the clamp, a bracket head adjustably mounted on said arm and having a fork at its outer end with longitudinal slots therein and provided at opposite sides with outwardly facing shoulders and inwardly and backwardly inclined cam faces extending from the shoulders, a perforating disc in said fork, a shaft for the disc bodily movable in the slots of the fork, means for continuous

ly rotating the shaft and disc, a pair of bearing members mounted on the shaft at opposite sides of the fork and having inwardly facing shoulders adapted to seat against the shoulders of the bracket head, springs between the inner rear portion of the bracket head and the inner ends of said bearing arms for drawing the bearing members and the shaft backwardly to unseat the shoulders of the bearing member and retract the perforating disc, a cam shaft mounted in the lower rear portion of the bracket head, cams on the cam shaft disposed in line with the rear edges of the bearing members and trip released means connected to the cam shaft for normally urging the cams against said bearing members to advance the shoulders thereof over said cam faces and beneath the shoulders of the bracket head.

In testimony whereof I affix my signature.

WESLEY P. SHOMAKER.
